UNITED STATES PATENT OFFICE.

STERLING H. CAMPBELL, OF ST. LOUIS, MISSOURI.

JOURNAL-BEARING WEDGE.

1,315,007.

Specification of Letters Patent. Patented Sept. 2, 1919.

Application filed April 11, 1919. Serial No. 289,405.

To all whom it may concern:

Be it known that I, STERLING H. CAMPBELL, a citizen of the United States of America, residing at the city of St. Louis, State of Missouri, United States of America, have invented a certain new and useful Journal-Bearing Wedge, of which the following is such a full, clear, and exact description as will enable any one skilled in the art to 10 which it appertains to make and use the same, reference being had to the accompanying drawings, forming part of this specification.

My invention relates to a journal bearing wedge for railway cars, its objects being to 15 produce a wedge which combines the advantageous features of lightness with sufficient strength, excellent wearing quality, low cost of manufacture, and means for minimizing if not wholly preventing undue 20 heating of the journal and associated parts in operation. Specifically, my invention relates to a one-piece hollow wedge of the type illustrated in Fig. 10 of my United States Patent No. 1,022,400 wherein the walls of 25 the wedge are of substantially uniform thickness to permit satisfactory annealing. The wedge described in said patent was found to be unsatisfactory on account of insufficient strength of the front and rear walls 30 and in that the difficulties in casting it precluded its manufacture at satisfactory cost. In the wedge herein described these disadvantages are avoided and means for keeping the wedge cool in operation have been 35 provided.

In the accompanying drawings, Figure 1 is a vertical section of the M. C. B. standard oil box to which my improved wedge is applied, Fig. 2 is a horizontal longitudinal section along the line 2—2 of Fig. 1 showing a portion of the wedge in plan view. Fig. 3 is a transverse section of the wedge along the line 3—3 of Fig. 2.

1 represents a journal box having a cover 45 2 and dust guard 11, all of standard design, the cover being held closed by spring 3 extending only partly across the upper part of the opening of the journal box whereby space is afforded for passage of air at the 50 sides of the spring and through the opening provided by the clearance between the upper edge of the cover and the box as indicated in the drawing. 4 represents the bearing portion of the car axle, 5 the brass, and 6 the journal bearing wedge embodying my invention.

The walls of the wedge are of uniform thickness, the lower surfaces, both horizontal and inclined, conform to the surfaces of the brass so that all portions of the lower 60 surfaces of the wedge are adapted to form a part of the bearing surface. In like manner all parts of the top surface 7 of the wedge within the outer limits of the area of engagement of the wedge with the journal 65 box form parts of a single cylindrical surface and are adapted to engage in operation with the journal box and serve as part of the bearing surface. The top surface of the wedge is connected to and supported from 70 the bottom surface 8 by spaced integral webs 9 which are only of sufficient number to provide the necessary supporting strength and are so distributed as not to substantially interfere with the circulation of the air 75 from one part of the interior of the wedge to another. The sides of the wedge are provided with a plurality of openings 10, preferably oppositely positioned, and communicating with the hollow interior of the wedge. 80 The front and end walls of the wedge are subjected to severe shocks in the operation of a car and in order that all the walls of the wedge be of uniform thickness and at the same time the wedge as a whole made relatively light it is essential that these front and end walls be not weakened by any openings. It has also been found that when the 85 core print openings are positioned in the front and rear walls the pocketing of gases 90 usually prevents proper filling of the mold with metal. By arranging the core to form a plurality of openings in the lateral walls and spaced as shown, all difficulty of making a good casting is overcome; the positions 95 of the holes are such that they do not disadvantageously weaken the casting; and they form an exceedingly useful function in the wedge since their position along the greatest length of the wedge produces a short path 100 from the center line of the wedge to the exterior whereby excellent ventilation is secured. It has been found in practice that journal boxes equipped with wedges constructed in accordance with my invention 105 seldom, if ever, become unduly hot and this is to be attributed to the fact that heated air is discharged from the interior of the wedge into the relatively large spaces between the wedge and the walls of the box 110 whence it may escape from the box either under the upper portion of the cover or past

the dust guard. The rotation of the axle tends to produce an air circulation in the upper part of the box along the axes of opposing openings in the wedge.

5. From the foregoing description it will be observed that my improved wedge has excellent wearing qualities by reason of having all of its upper and lower surfaces positioned to act as parts of the wearing surfaces; that it combines lightness with sufficient strength thus resulting in low cost of manufacture and greater convenience in handling; and finally is so constructed as to facilitate the rapid dissipation of frictional 10 heat developed in the operation of the journal as distinguished from the heat retaining qualities of solid wedges or those in which closed air pockets are formed.

Having fully described my invention, 20 what I claim as new and desire to secure by Letters Patent of the United States is:

1. A hollow journal bearing wedge having a plurality of ventilating openings in its lateral walls communicating with the interior of the wedge.

2. A hollow journal bearing wedge having all its walls of substantially uniform thickness, the front and rear walls being imperforate and the lateral walls being provided with a plurality of spaced ventilating 30 openings communicating with the interior of the wedge.

3. A hollow journal bearing wedge having its entire upper face in a single cylindrical surface, its front and rear walls imperforate, and its lateral walls provided with spaced 35 openings communicating with the interior of the wedge.

4. A hollow one piece journal bearing wedge having a plurality of oppositely positioned openings in its lateral walls and communicating with the interior of the wedge.

5. A hollow journal bearing wedge having a plurality of spaced short integral webs 45 connecting its top and bottom walls and a plurality of spaced ventilating openings in its lateral walls communicating with the interior of the wedge.

6. A hollow journal bearing wedge having all its walls of substantially uniform thickness, substantially the entire upper and lower surfaces of the wedge being adapted to form bearing surfaces, integral spaced webs connecting the top and bottom walls of the 55 wedge and permitting communication between all parts of the interior of the wedge, said wedge also having imperforate front and rear walls and spaced oppositely located openings in its lateral walls communicating with the interior of the wedge.

In testimony whereof, I have hereunto set my hand and affixed my seal.

STERLING H. CAMPBELL. [I. S.]
